(57) CLAIM

The ornamental design for a neck wrap, as shown and described.

DESCRIPTION

FIG. 1 is a perspective view of a neck wrap, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective thereof, in which a person, in broken line, is shown wearing the neck wrap.

The broken line showing of a person is for the purpose of illustrating environment and forms no part of the claimed design.

1 Claim, 6 Drawing Sheets
